[57] **CLAIM**

The ornamental design for an illuminated fabric scarf, as shown and described.

DESCRIPTION

FIG. 1 is a front elevational view of an illuminated fabric scarf showing my new design wherein lighting included within the scarf behind the fabric illuminates the scarf;

FIG. 2 is a top elevational view thereof;

FIG. 3 is a rear elevational view thereof;

FIG. 4 is an end view thereof;

FIG. 5 is a front perspective view thereof, the broken line showing of the human form is for illustrative purposes only and forms no part of the claimed design; and,

FIG. 6 is a sectional view taken along line 6—6 of FIG. 1.
